US0D1002177S

(12) United States Design Patent (10) Patent No.: US D1,002,177 S
(45) Date of Patent: * Oct. 24, 2023

(54) TOTE BAG

(71) Applicant: ROTHY'S, INC., San Francisco, CA (US)

(72) Inventors: La Vion Gibson, San Francisco, CA (US); Manon Julien, London (GB)

(73) Assignee: ROTHY'S, INC., San Francisco, CA (US)

() Term: 15 Years

(21) Appl. No.: 29/825,097

(22) Filed: Jan. 28, 2022

(51) LOC (14) Cl. 03-01

(52) U.S. Cl.

USPC D3/201
